(57) **CLAIM**

The ornamental design for a heel component for footwear as shown and described.

DESCRIPTION

FIG. 1 is a front view of an embodiment of a heel component for footwear showing the new design;

FIG. 2 is a rear view thereof;

FIG. 3 is a top view thereof;

FIG. 4 is a bottom view thereof;

FIG. 5 is a left side view of the heel component for footwear of FIG. 1, where the right side view is a mirror image of the left side view; and,

FIG. 6 is a side perspective view of the heel component for footwear of FIG. 1 showing the heel component in an article of footwear.

The broken lines in FIG. 6 represent a footwear environment that form no part of the claimed design.

1 Claim, 3 Drawing Sheets
